SEALANT APPLICATOR

Ralph J. Cook, Torrance, Calif., assignor to Products Research & Chemical Corporation, Burbank, Calif.

Filed Jan. 8, 1970, Ser. No. 20,826

Term of patent 14 years

Int. Cl. D8—02

U.S. Cl. D8—14.1

FIG. 1 is a perspective view of a sealant applicator taken from the left rear thereof showing my new design;

FIG. 2 is a right side elevational view;

FIG. 3 is a rear elevational view; and

FIG. 4 is a front elevational view.

The fragmentary broken line showing of a sealant dispensing nozzle and air pressure line in FIGS. 1 and 2 is for purposes of illustration only.

I claim:

The ornamental design for a sealant applicator, as shown and described.
